(57) **CLAIM**

The ornamental design for the optical communications device housing portion, as shown and described.

DESCRIPTION

FIG. 1 is a perspective view of the optical communications device housing portion in accordance with a first embodiment of our design;

FIG. 2 is a top plan view of the optical communications device housing portion in accordance with the first embodiment of our design;

FIG. 3 is a front elevational view of the optical communications device housing portion in accordance with the first embodiment of our design;

FIG. 4 is a right side elevational view of the optical communications device housing portion in accordance with the first embodiment of our design;

FIG. 5 is a left side elevational view of the optical communications device housing portion in accordance with the first embodiment of our design;

FIG. 6 is a perspective view of the optical communications device housing portion in accordance with a second embodiment of our design;

FIG. 7 is a top plan view of the optical communications device housing portion in accordance with the second embodiment of our design;

FIG. 8 is a front elevational view of the optical communications device housing portion in accordance with the second embodiment of our design;

FIG. 9 is a right side elevational view of the optical communications device housing portion in accordance with the second embodiment of our design; and,

FIG. 10 is a left side elevational view of the optical communications device housing portion in accordance with the second embodiment of our design.

The broken lines show the environment in which the article is used and are not considered part of the design claimed.
